UNITED STATES PATENT OFFICE.

NATHANIEL B. ROGERS, OF DANBURY, CONNECTICUT.

DESIGN FOR A LIGHTING-FIXTURE.

56,031.

Specification for Design.

Patented Aug. 10, 1920.

Application filed April 19, 1920. Serial No. 375,182. Term of patent 7 years.

To all whom it may concern:

Be it known that I, NATHANIEL B. ROGERS, a citizen of the United States, residing at Danbury, in the county of Fairfield and State of Connecticut, have invented a new, original, and ornamental Design for a Lighting-Fixture, of which the following is a specification, reference being had to the accompanying drawing, forming part thereof.

Referring to the drawings—

Figure 1 is a front elevation of a lighting fixture, showing my new design, and Fig. 2 a side elevation thereof.

I claim:

The original design for a lighting fixture, as shown.

NATHANIEL B. ROGERS.
